UNITED STATES PATENT OFFICE

ALBERTO BAGNULO, OF PARIS, FRANCE

LIQUID FUEL ENGINE

Application filed July 16, 1930, Serial No. 468,416, and in France July 27, 1929.

The present invention relates to internal combustion engines and particularly to those in which the fuel, prior to being transformed into an explosive mixture by addition of air, is vaporized and heated in a special vaporization chamber, in the shape of a bulb, mounted on the cylinder, the interior of said bulb communicating with the interior of the cylinder through an orifice.

The engines according to the present invention are provided with the vaporization chambers already described in my co-pending application Serial No. 320,176, filed November 17, 1928. These chambers comprise a spherical portion described about a focal point, a spring mounted valve of short stroke without external control being disposed in axial alignment with the orifice communicating with the cylinder, and that portion of the internal surface of the chamber which is adjacent to said valve being tangential to the said spherical portion. The movement of this valve is not controlled by cams or other mechanical elements but is controlled by the differences between the atmospheric pressure and the pressure inside the chamber. The fuel is admitted and accumulates in the space behind said valve, and is injected, in the form of oblique jets, into the chamber when the valve opens under the influence of the vacuum produced by the suction stroke of the engine piston. As is shown in the drawing, the valve and adjacent portion of the vaporization chamber are disposed symmetrically with reference to the axis joining the inlet and outlet of the vaporization chamber. The valve may be normally retained on its seat by a spring.

In my aforesaid application, I have also provided, in the focal point of the chamber, a heating plug member which heats the fuel vapour and is itself heated by an externally disposed source of electricity.

According to the present invention, the orifice for the passage of the gases between the vaporization and ignition chamber and the cylinder is designed in a special manner, and the vaporization chamber is provided internally with a metallic protuberance of such a kind that:

1. During the compression stage, the air coming from the cylinder aspirates the fuel which has remained liquid and collected, in the bulb, in the vicinity of the communication orifice, and at the same time, causes active agitation of the gases in the interior of the bulb and a jet of flame due to a preliminary combustion, said jet being directed on to the metallic protuberance and keeping it at ignition temperature, even when the engine is slowed down.

2. Towards the close of this stage, and in consequence of the increase of pressure in the bulb, following this commencement of combustion, the gaseous mass contained in the bulb is projected into the interior of the cylinder and aspirates the air of the cylinder laterally in relation to the jet of ignited gas, thus allowing agitation and good combustion, prior to or concurrently with the expansion.

The invention will be more clearly understood with reference to the accompanying drawing and the description relating thereto, which represents an embodiment, which is given by way of example and is not to be considered as restrictive.

In the drawing, the vaporization and ignition chamber B is mounted, in any convenient manner, on the cylinder H. At the side on which it is secured to the cylinder, the vaporization chamber comprises a double Venturi tube or cone V, which opens, at V on the one hand, into the interior of the bulb, and at V' on the other hand, into the interior of the cylinder. The two cones are disposed with their apices facing one another, and are provided with a common orifice F, which forms the communicating passage between the bulb B and the cylinder H.

The cone or Venturi tube V, inside the bulb, is surrounded by an annular space C and is provided, in the zone of maximum depression, with apertures T opening towards the base of the cone.

The cone V', situated inside the cylinder H, is also provided with a series of openings T', which are intended to aspirate the air remaining in the cylinder, under the same

conditions as in ordinary blowpipes or Bunsen burners.

At the top of the chamber B, and in the part most remote from the cone V, is a baffle A, formed by a mass of metal (preferably unoxidizable), which may be of any suitable shape.

The fuel is admitted through the pipe G, the mouth of which is controlled by a valve, or equivalent member S. This valve has a short stroke, that is its displacements are very small, and it directs obliquely along the walls of the chamber the streamlets of liquid fuel entering the chamber.

The method of operating is as follows: When the engine is not running under high compression, the vaporization chamber is preheated in the manner usual for semi-Diesel engines.

The fuel is admitted through the pipe G and valve S. It is sprayed in streamlets and runs along the walls of the vaporization chamber B until it reaches the cup C. The fuel may also be introduced direct into C by a small injector mounted on the side of the vaporization chamber and on a level with said cup C.

During the compression stage, the air entering the vaporization chamber from the cylinder by way of the orifice F and cone V, aspirates the fuel, which has collected in the cup C, through the bores T, thus assuring the mixing of this accumulated fuel with the remainder of the fuel already vaporized in the hot chamber.

A preliminary combustion or preliminary flame is thus produced in the interior of the chamber B, which flame directly heats the metallic mass A while a very active agitation is effected, in the interior of the bulb, in consequence of the eddies set up as previously stated.

This process keeps the mass A hot, even when the engine is running at very low speed, and consequently, ignition is assured, even when the engine is slowing down.

When as the result of the combustion, the pressure in the chamber increases, the entire mass of gas is projected into the interior of the cylinder, through the Venturi cones, the combustion being completed by the air which has remained in the cylinder and is aspirated by means of the openings T' in the cone V', in conformity with the well known phenomenon in blowpipes and Bunsen burners.

The cone projecting into the chamber serves to guide the flame along the axis of the chamber toward the fuel valve and also to accelerate the flame, while the fuel in entering avoids the flame and passes along the walls of the vaporization chamber, is collected in the cup C below, and is picked up by the eddies caused by the entrance of the flame adjacent to the cup, which contributes

to the rapid atomization and vaporization of the fuel.

It will be understood that the invention can be embodied in numerous ways, in addition to that given simply by way of example, in respect of the details of shape and arrangement of the members, their design, the nature of the materials of which they are constructed, etc. The devices which it comprises, especially the Venturi cones and the massive protuberance in the interior of the bulb may be employed separately or in combination.

What I claim and desire to secure by Letters Patent is:—

1. In an internal combustion engine, a vaporization chamber mounted on the engine cylinder, a spring mounted valve of short stroke actuated by fuel pressure, aligned with the axis of said chamber and opening towards the interior thereof, one portion of the interior surface of said chamber being substantially spherical, and another portion of said surface adjacent to said valve being tangential to the said substantially spherical portion of said surface, two coaxial Venturi tubes in the form of truncated cones with their small bases superposed and opening respectively into said cylinder and into said chamber, said tube opening into the Venturi chamber being positioned substantially opposite said valve and extending a substantial distance within said chamber, and an annular cup member formed by the side and bottom walls of said vaporization chamber and by the outer surface of the Venturi tube extending into said chamber, the Venturi tube extending into said chamber being obliquely laterally apertured in a line intersecting the base of the cone constituting said Venturi tube.

2. In an internal combustion engine, a vaporization chamber mounted on the engine cylinder, a spring mounted valve of short stroke actuated by fuel pressure aligned with the axis of said chamber and opening towards the interior thereof, one portion of the interior surface of said chamber being substantially spherical, and another portion of said surface adjacent to said valve being tangential to the said substantially spherical portion of said surface, two coaxial Venturi tubes in the form of truncated cones with their small bases superposed, opening respectively into said cylinder and into said chamber, the Venturi tube opening into said chamber being positioned substantially opposite said valve and extending a substantial distance within said chamber, and an annular cup member formed by the side and bottom walls of said vaporization chamber and by the outer surface of the Venturi tube extending into said chamber, the Venturi tube extending into said chamber being obliquely laterally apertured in a line intersecting the base of the

cone constituting said Venturi tube, and the Venturi tube extending into said cylinder being laterally apertured.

3. In an internal combustion engine, a gasification chamber mounted upon the cylinder of the engine, injection means for injecting combustible fluid into said chamber, said cylinder and chamber being interconnected by a passage in the form of two Venturi tubes united by their small bases and having the frusto conical portions thereof disposed on an axis coincident with the axis of said injection means, one of said frusto conical portions extending a substantial distance into said chamber and forming with the walls thereof an annular trough for receiving combustible fluid, and canals forming intercommunicating passages between said trough and the interior of said Venturi tubes.

ALBERTO BAGNULO.
